CRANKCASE AIR-PRESSURE CONTROL MEANS

Walter G. Winkels, United States Navy, and Thomas W. Ashcroft, Beloit, Wis., assignors to Fairbanks, Morse & Co., Chicago, Ill., a corporation of Illinois

Application April 23, 1943, Serial No. 484,194

9 Claims. (Cl. 121—194)

This invention relates to crankcase air-pressure control means, and more particularly to an improved device for controlling air-pressure within a substantially closed crankcase of an internal combustion engine, pump, compressor or the like.

A principal object of the present invention resides in the provision of a novel and effective control device for substantially closed crankcases of engines and the like, which affords crankcase compression relief and air-pressure control in a manner generally to prevent above-atmospheric air pressures within the crankcase during engine operation, and more particularly, to facilitate maintenance of sub-atmospheric pressures in the crankcase, even to the extent of a slight negative pressure or partial vacuum therein, throughout at least a greater portion of each cycle of engine piston operation, whereby there is thus prevented or very materially reduced such loss of lubricating fluid from the crankcase interior, as otherwise would tend to occur by reason of above-atmospheric air pressure in the crankcase tending to force lubricant outwardly, as through cylinder ports, crankcase joints, and past such operating parts of the engine which extend through wall portions of the crankcase.

Another object of the invention resides in the provisions of a relatively compact and effective crankcase air control device of the character indicated, adapted for controlling the pressure within the crankcase by affording periodic air release from the crankcase during engine operation, wherein the device embodies a lubricant condensing chamber and lubricant absorbing means therein, for the removal of lubricant from the crankcase air released through the device, and controlled means for effecting return of the lubricant thus removed, to the crankcase.

A further object of the invention is to provide an improved device for the purpose indicated, which utilizes an operating part of the engine as an active element of the device, and which provides an oil entrapping and condensing shield at the outlet thereof, for insuring against discharge of oil particles into the atmosphere about the engine.

Other objects and advantages of the invention will appear from the following description of a preferred embodiment thereof as exemplified in the accompanying drawing, in which:

Fig. 1 is a longitudinal elevation partly in section, of an internal combustion engine embodying the presently improved crankcase air control device;

Fig. 2 is an enlarged sectional elevation of an 55

upper portion of the crankcase, as taken from the line 2—2 in Fig. 1, showing the crankcase device therein, the view also illustrating a magneto device in driven connection with a drive gear in the crankcase portion shown, and

Fig. 3 is a sectional elevation through the device, as viewed from line 3—3 in Fig. 2.

Referring to the drawing by suitable characters of reference, the improved control device in the embodiment presently preferred and herein illustrated, is shown by way of an example of its application, in association with an internal combustion engine of closed crankcase type, indicated generally at 10. Briefly, the engine shown by Fig. 1 includes a frame assembly providing a cylinder 11 and a crankcase 12, a crankshaft 14 in the crankcase, a piston 15 operable in cylinder 11, and a connecting rod 16 between the piston and crankshaft. A magneto generator 18 (Fig. 2) provided for supplying engine ignition current, is arranged externally to and preferably above the crankcase 12 adjacent an upward extension 19 of the crankcase. An opening 20 in one wall 22 of crankcase extension 19 affords projection of the magneto shaft coupling element 23 into the chamber 24 provided by the extension 19, for driven connection with a gear 26 therein forming an element of a gear train comprising enmeshing gears 26, 27, 28 and 30. The latter gear 30 is located on and driven by the crankshaft 14, so that the magneto is operated from the crankshaft through the described gear train. For a purpose hereinafter to appear, the gear-drive ratio of the gear train is such that the gear 26 and hence the magneto shaft, will be rotated at engine crankshaft speed, although not necessarily in the same direction as crankshaft rotation.

Since the chamber 24 of extension 19 is in full communication with the main crankcase chamber 31, as appears in Fig. 2, the opening 20 receiving the magneto shaft coupling 23 therethrough, is sealed about the magneto frame extension 32 at the opening in any suitable manner, as by a gasket indicated at 34.

The device of the present invention is located in the crankcase extension 19, as appears in Figs. 2 and 3, and employs the magneto drive gear 26 as an element thereof. An aperture 35 is provided in the outer vertical wall 36 of crankcase extension 19, giving access to the extension chamber 24, and this opening is normally closed by a removable closure plate or cover member 38 which is suitably sealed at the opening by a gasket 39 or like means. Centrally of the closure plate and

projecting horizontally and inwardly therefrom, is a gear support or spindle 40 which by preference, is formed integrally with the closure. The spindle is reduced as at 42 to provide a shoulder 43 and a gear journaling seat 44 over the inner longitudinal end portion of the spindle. Gear 26 rotatably received on spindle seat 44 and against shoulder 43, is formed to provide a cylindrical hub extension 46 having an end wall 47 transversely notched or recessed as at 48, for driving connection to the magneto shaft coupling 23 by means of coupling lugs 50 engaged in the gear hub recesses 48 (Fig. 2).

The spindle 40 is interiorly recessed longitudinally thereof, to provide a chamber 51 open at its outer end 52 and closed at its opposite or inner end 54 by a spindle end wall 55, the chamber as shown by Figs. 2 and 3, preferably being of cylindrical form and tapered convergently toward the open end 52 thereof. Communication between the spindle chamber 51 and the chamber 24 in the crankcase extension 19, is effected through an upper inlet port 56 through the spindle wall at the inner end 54 of the chamber 51, and a diametrically opposite outlet port 58 of lesser capacity. The hub extension 46 of gear 26 which overlies the spindle portion in which the ports 56 and 58 are located, is here utilized as a rotary valve element for controlling port communication with the chamber 24 of the crankcase extension 19. To this end, the gear hub is provided with an aperture 59 preferably of a diameter equivalent to the diameter of the larger port 56 in the spindle, located for successive registry with the ports 56 and 58 during rotation of the gear 26.

A discharge or outlet attachment generally indicated at 60, is suitably removably secured on the external face of the closure member 38 in registry with the open end 52 of the spindle chamber 51, and includes a casing 62 and an upwardly directed discharge neck 63 open at its upper end 64. A protective cap or hood 66 overlying the open end of discharge neck 63 and projecting laterally on opposite sides thereof, as at 67 (Fig. 3), provides for downward air discharge through the openings 68. As indicated, the attachment casing 62 is sealed in its assembly connection to the closure 38 as by a suitable gasket element 70.

Opposed longitudinal channels 71 in the walls of the spindle chamber 51, afford a support for a removable screen 72 preferably of coarse wire mesh which extends horizontally through the chamber 51 and the chamber 74 provided by the attachment casing 62. Bearing on the upper surface of the screen 72 within the chamber 51, is an oil-absorbent member of felt pad 75 which may have its longitudinal margins 76 compressed in the channels 71 as shown. The pad further may be attached directly to the screen by a suitable clasp or staple element 78, so that the screen and pad may be inserted or removed as a unit.

In the operation of the presently improved crankcase air control device, the gear 26 is set initially such that its hub valve aperture 59 is in full registry with the upper spindle port 56, when the engine piston is near the crank end of its stroke. Thereafter and during engine operation, the gear 26 rotated from the crankshaft at engine speed, will establish successively, a relatively short-period opening of the crankcase chamber to the atmosphere through the chamber 24 of crankcase extension 19, gear valve aperture 59 in register with spindle port 56, spindle chamber 51, chamber 74 of attachment or shield

60, and through neck 63 and openings 68, and a somewhat shorter-period opening of the crankcase chamber to the spindle chamber 51 in the zone of chamber port 58, through registry of the gear hub aperture 59 with the port 58, occurring one-half a revolution later and as the piston approaches the head end of its stroke. In the first stage of its cyclic function as above indicated, and when there is a tendency for the air in the crankcase to be under a pressure slightly above atmospheric as a result of piston displacement toward the crank end of its stroke, the control device then becomes effective to vent to atmosphere some of the crankcase air, whereby to relieve the slight, above-atmospheric air pressure in the crankcase so as immediately to restore the crankcase air pressure to atmospheric or sub-atmospheric value. Since in the normal function of the engine, some oil will be entrapped in the air thus released, this oil must be removed in the compression-relieving process. To this end, the spindle chamber 51 through which the oil-laden crankcase air passes, serves in the presently preferred embodiment of the device, as an oil condensing chamber for removing some of the oil from the air vented therethrough. The oil thus condensed in the chamber, collects on and is absorbed by the felt pad 75 on screen 72, and hence is prevented from passing to the exterior of the device. The felt pad 75 being centrally disposed in chamber 51 and hence directly in the path of air flow therethrough, is of itself an effective agency for direct absorption of oil particles entrapped in the air vented through the chamber. Thus by the condensing function of the chamber 51 and the oil absorbing action of the pad 75 therein, a major portion of the oil in the vented crankcase air, will be removed for ultimate return to the crankcase. Such small portion of oil as may remain in the air attaining the chamber 74 and neck 63 of the attachment 60, will be condensed therein and will collect in the zones of chambers 74 and 51 below the screen 72. Similarly, oil accumulated by the absorbent pad 75 ultimately will drip through the screen into the lower portion of chamber 51. It is to be noted that the wire mesh screen 72 has an important function in the present assembly, in that it effectively prevents the air vented to atmosphere through the chambers 51 and 74, from picking up any of the oil accumulating below the screen.

In the second stage of the operational cycle, the gear aperture 59 registers with the lower spindle port 58 as the engine piston approaches top dead center and when there is a slight but appreciable suction or negative pressure in the crankcase as a consequence in part, of such piston displacement. Upon opening of the port 58, the oil accumulated in the chamber below the screen 72 and collecting in the zone of the port 58 by reason of the tapered form of chamber 51, will be returned by suction through port 58 and gear aperture 59 into the chamber 24 of crankcase extension 19, and thence into the engine crankcase. In the normal and intended function of the device, atmospheric air will not be drawn into the crankcase in this stage of operation, this by reason of the limited capacity of the port 58 and the relatively short period in which it is opened to the crankcase by valve port 59, which thus enables the lubricant pool in chamber 51 and above the port 58, to act as an air seal even during the suction return of a portion thereof to the crankcase.

From the foregoing description of operation, it will appear now that the control device in its function to relieve crankcase compression in the compression cycle of engine piston operation, and to prevent suction return of air to the crankcase in the cycle of piston suction effect in the crankcase, affords a fully effective means for controlling crankcase air pressures to the extent that it prevents existence of above-atmospheric pressure therein, and facilitates maintenance of sub-atmospheric or even a slight negative pressure or slight vacuum in the crankcase, during at least the greater portion of each complete cycle of engine piston operation. As a consequence of the subatmospheric pressures or slight vacuum thus established in the crankcase, the crankcase lubricating fluid is most effectively retained therein, against leakage or loss to the crankcase exterior, as through cylinder ports, crankcase joints, and past such operating parts of the engine which extend through wall portions of the crankcase. The resulting suction retention of lubricating fluid in the crankcase, together with the return thereto, of fluid condensed and otherwise removed from the crankcase air vented to atmosphere through the present novel control device, effectively conserves the crankcase lubricating fluid to an important degree, as will be now fully appreciated.

The present crankcase air-pressure control device fully attains the objects herein expressed, and additionally, presents a relatively compact mechanism having but few parts, and wherein the operating valve element thereof is embodied by preference, in the engine driven magneto drive gear of the engine assembly illustrated. Although the device is shown herein as applied to an upper extension of the crankcase for convenience in effecting the illustrated drive connection to the engine magneto located externally above the crankcase, it will be understood that the device may be readily located in any other zone of the crankcase, with appropriate relocation of the engine shaft drive connection to the rotary port-control element 26 of the device.

While the present disclosure relates to a single preferred embodiment of the invention, it will be understood that alterations or modifications therein may be made without departing from the spirit and intended scope of the invention as defined by the appended claims.

We claim:

1. A control device of the character described for a substantially closed crankcase, comprising means providing a chamber open to the atmosphere, means including a valve, for establishing atmospheric communication with the crankcase through said chamber at least once in each cycle of developed pressure and suction in the crankcase, and means controlled by the valve, for establishing in the suction period of said cycle, communication between said chamber and the crankcase.

2. A control device of the character described for a substantially closed crankcase, comprising a member having a chamber therein open to the atmosphere and provided with spaced ports for communication with the crankcase interior, and valve means operatively supported by said member, adapted for opening said ports to the crankcase interior in each cycle of developed pressure and suction in the crankcase, such that one of said ports is thereby opened in each period of developed pressure and the other port opened

in each period of developed suction in the crankcase.

3. A control device of the character described for a substantially closed crankcase, comprising a member extending within the engine crankcase and provided with a chamber therein open to the atmosphere, said member having spaced ports communicating with said chamber, valve means in control of said ports and operable for successively opening the ports to the crankcase interior, and valve actuating means for operating said valve means in timed relation to the cycle of developed pressure and suction in the crankcase, the operation of said valve means thereby serving to open one of said ports in the periods of piston developed pressure and the other port in the periods of piston developed suction in the crankcase.

4. A crankcase air-pressure control device for internal combustion engines, comprising a member extending within the engine crankcase and provided with a chamber therein open to the atmosphere, said member having spaced ports communicating with said chamber, an element rotatable on said member in a position to overlie said ports and having an opening therein located for registry with said ports, said element during rotation serving through said opening therein, to open said ports to the crankcase interior, and engine controlled means for operating said element in timed relation to the cycle of piston developed pressure and suction in the crankcase, the operation of said element thereby, serving to open one of said ports in the periods of piston developed pressure and the other port in the periods of piston developed suction in the crankcase.

5. A crankcase air-pressure control device for internal combustion engines, comprising a member providing a lubricant condensing chamber for lubricant-laden air, said chamber being open to atmosphere and having spaced ports for communication with the crankcase interior, and engine controlled valve means in control of said ports, adapted for opening one of said ports in the period of piston developed pressure in the crankcase, to permit passage of lubricant-laden crankcase air through said condensing chamber, and for opening the other of said ports in the period of crankcase suction, to effect suction return to the crankcase of lubricant condensed in said chamber.

6. A crankcase air-pressure control device for internal combustion engines, comprising a member projecting within the engine crankcase and having a chamber therein open to the atmosphere, said member being provided with spaced ports affording communication between the chamber and the crankcase interior, lubricant collector means in said chamber, and an engine actuated rotary valve on said member, effective for opening one of said ports in the period of piston developed pressure in the crankcase, to permit discharge of lubricant-laden crankcase air through said chamber, and for opening the other of said ports in the period of crankcase suction, to effect suction return to the crankcase of lubricant collected in said chamber by said collector means.

7. A crankcase air-pressure control device for internal combustion engines, comprising a member extending into the engine crankcase and providing a chamber therein open to the crankcase exterior, said chamber having spaced ports for communication with the crankcase interior, a

chambered outlet attachment in registry with the open end of said chamber, an engine controlled valve on said member, adapted for opening one of said ports to the crankcase interior in the period of piston developed pressure in the crankcase, for permitting discharge of lubricant-laden crankcase air through said chamber and said chambered outlet attachment, and means including the chambered outlet attachment, effective for condensing and collecting lubricant from the crankcase air discharged through said chamber and attachment, said valve being effective in the period of crankcase suction, to open the other of said ports for the suction return to the crankcase of lubricant collected by said means.

8. The combination with an internal combustion engine providing an engine driven gear in the crankcase for operating a device adjunctive to the engine organization, of a crankcase air-pressure control device comprising a member extending within the crankcase and providing a bearing support for said gear, said member having a chamber therein open to the atmosphere and spaced ports for communication with the crankcase interior, said gear being adapted as a control valve for said ports, operable for opening

one of said ports to the crankcase interior in each period of piston developed pressure in the crankcase, and for opening another of the ports thereto in each period of piston developed suction in the crankcase.

9. The combination with an internal combustion engine providing an engine driven gear in the crankcase having a hub extension for driving connection with a device adjunctive to the engine organization, of a crankcase air-pressure control device comprising a member extending within the crankcase and providing a bearing support for said gear and hub extension, said member providing a chamber therein open to the atmosphere at its outer end, and having spaced ports near the inner end of the chamber, underlying the hub extension of said gear, and said gear hub extension having an opening therein registerable with said ports during gear rotation, provided for opening said ports to the crankcase interior in each cycle of piston developed pressure and suction in the crankcase, such that one of said ports is opened thereby in the period of piston developed pressure and another port opened in the period of piston developed suction.
